UNITED STATES PATENT OFFICE.

ARVID R. NELSON, OF MEDIAPOLIS, IOWA.

MANURE-LOADER.

1,392,653.

Specification of Letters Patent.

Patented Oct. 4, 1921.

Application filed June 23, 1920. Serial No. 391,065.

To all whom it may concern:

Be it known that ARVID R. NELSON, a citizen of the United States, residing at Mediapolis, in the county of Des Moines and 5 State of Iowa, has invented certain new and useful Improvements in a Manure-Loader, of which the following is a specification, reference being had therein to the accompanying drawings.

10 This invention relates to an improvement in manure loaders, and the object of the invention is the construction of a loading apparatus which is susceptible of handling sand, gravel, coal, stones, manure, or any 15 substance that the operator desires to load or unload.

Another object of the invention is the construction of an apparatus, which includes an efficient and peculiarly constructed and 20 equipped hopper, in conjunction with an elevating device, whereby the hopper can be loaded and then the contents of the hopper dumped into a suitable conveyance for the expeditious handling of the material.

25 With these and other objects in view, my invention comprises certain novel combinations, constructions and arrangements of parts as will be hereinafter described, illustrated in the accompanying drawings, and 30 more particularly pointed out in the appended claims.

In the drawings:

Figure 1 is an end view of an apparatus constructed in accordance with the present 35 invention.

Fig. 2 is a rear elevated view of the apparatus.

Fig. 3 is a transverse sectional view of the apparatus.

40 Fig. 4 is a horizontal sectional view of the apparatus, taken on line 4—4, Fig. 1, and looking in the direction of the arrows.

Fig. 5 is an enlarged fragmentary perspective view of the hopper.

45 Referring to the drawings by numerals, 1 comprises the runners of the main frame, and 2 are the end standards supported upon the runners 1.

At each side of the frame, constituted by 50 said runners 1 and standards 2, and supported at their ends in the standards 2, are inclined rods 3, constituting an inclined track-way, at each end, upon which travels the rollers 4. The rollers 4 are journaled 55 upon shafts 5 of the brackets 6; brackets 6 are suitably secured to the ends 7 of the hop-

per-frame; this hopper-frame includes the ends 7, the back 8 and the front piece 9. A door 10 is hinged, at 11, to the front piece 9, which door 10 normally closes the front of 60 the hopper-frame, while the apparatus is being filled or loaded by the elevator 12. A scoop-like bottom 13 is pivotally mounted, at 14, on the ends 7 of the hopper-frame, this bottom 13 projecting beyond the front of the 65 hopper-frame, shown in Figs. 3 and 5; extending from the ends of this front portion of the bottom are lugs 15, which are engaged by latches 16 pivoted, at 17, upon the ends 7. Rods 18 are pivotally connected, at their 70 front ends, to the upper portion of the latches 16, and the rear ends of the rods slide in apertured lugs 19 formed integrally upon bracing strips 20. The rear ends of the rods are formed into eyes 21 and ropes 75 or cables 22 are fastened in these eyes; by the operator drawing rearwardly upon the cables or ropes 22, the latches 16 will be disengaged from the lugs 15, as shown in dotted lines in Fig. 3, permitting the scoop-like 80 bottom 13 to drop down and allow the contents of the hopper to be discharged into a waiting receptacle at the side of the apparatus or into a bin or upon a dump; as the case may be.

85 The device for holding the hopper within the frame, as shown in Fig. 1, comprises brackets 23, upon which are pivotally mounted, at 24, catches 25. These catches catch and hold the lower ends of the vertical 90 strips 20, until the catches are released, whereupon the hopper is allowed to move to its dumping position, as shown in dotted lines, Fig. 3. A coil spring 26 is fastened at one end to a standard 2 and its other end 95 is fastened to the inner end of the catch 25, so that these catches 25 have their outer hooked ends in position to be engaged by the lower ends of strips 20, as soon as the hopper is moved back into the frame, from 100 its dumping position (see dotted lines, Fig. 3) the catches snapping over the outer edges of the strips 20 and holding the hopper within the frame, while it is being loaded. To operate the catches 25 (see Fig. 4) I provide a pivotally mounted lever 27 (Fig. 2) to which lever 27 are connected the inner ends of rods 28, the outer ends of said rods being pivotally connected to the inner ends of the catches 25.

105 110 When the hopper is in its closed position within the supporting frame, Figs. 1 and 3,

the lower end of the hinged door 10 rests behind the lugs or stops 29 (Fig. 3) whereby the door is kept from swinging outwardly until the device is released for dumping, 5 then upon the scoop-like bottom 13 swinging downwardly, upon its pivots 14, as shown in Fig. 3, the lugs 29 will be removed from contact with the hinged door 10, allowing the door to swing outwardly, as 10 shown in dotted lines, Fig. 3. When the hopper is in its closed position upon the frame, the lugs 29, of the scoop-like bottom, will retain the hinged door 10 in a closed position, while the hopper is being loaded. 15 The elevator 12 is pivotally supported, at 30, upon the primary frame 31, which is slidably mounted upon the inner auxiliary frame 32; the auxiliary frame 32 is pivotally supported upon bolt 33 upon one of 20 the runners 1 of the main frame; this pivotal mounting of the frames 31 and 32, upon the main frame, permits the elevator to be swung to different horizontal positions upon the frame to enable the persons operating 25 the machine to more easily load the elevator 12.

A motor 34 is supported upon the auxiliary frame 32 and this motor operates the conveyer 35 of the elevator 12, through the 30 medium of a belt 36 and a sprocket chain 37.

The elevator 12 is provided with a brace 38, which brace is pivoted, at 39, upon the elevator 12 and the lower end of the brace is provided with pins 39, which pins are 35 adapted to extend into cross pieces 40 fastened to the frames 31 and 32 so that by adjusting the brace 38 to different cross pieces 40, a different inclination of the elevator 12 can be obtained, at the will of the 40 operator, for supporting the elevator and allowing the bottom of the same to reach farther outwardly, if need be, or by shoving in the primary frame 31, upon the auxiliary frame 32, the elevator can be placed closer 45 to the main frame, when required.

It will be understood that the loading of the elevator, by throwing the material upon the conveyer 35, will cause the material to be dumped into the hopper, and 50 upon the hopper being loaded, it can be dumped into a waiting vehicle at the side of the main frame under the hopper, and then the vehicle can be conveyed into a field or to any other suitable place and unloaded, while, 55 at the same time, a single operator with the apparatus can be loading the hopper again, through the medium of the elevator, so that the conveying vehicle can substantially be moving all the time, without any interruption, as the hopper will be ready to dump 60 immediately upon the vehicle being returned for a load.

My apparatus can be equipped with wheels, by attaching the wheels to the runners 1, in any ordinary manner, and I make

no claim for the placing of the apparatus on wheels, as this is an obvious expedient, if it is desired to more readily convey the apparatus from one place to another place, instead of drawing the same in any suitable 70 manner, upon the runners 1.

It is also to be understood that the apparatus is suitable for loading a great many materials into the hopper and thence dumping the same; therefore, I do not limit myself merely to the handling of manure but it is especially adapted for this purpose on the farm, when it is desired to load a manure spreader and save time in accomplishing this result. 75 80

While I have described, in the foregoing, the preferred embodiment of my invention, and have illustrated the same in the accompanying drawings, I wish it to be understood that I reserve the right to make such changes or alterations as shall appear to one skilled in the art to which this invention relates, and which changes or alterations shall fairly fall within the scope of the appended claims. 85 90

What I claim is:

1. In an apparatus of the class described, the combination with a frame, of pairs of rods having their ends extending into said frame positioned at the ends of the frame, a 95 roller between and traveling upon the rods of each pair, a hopper within said frame, said hopper provided with brackets at its ends, said brackets provided with stub shafts extending into said rollers, locking means for holding said hopper in a fixed position upon said frame, and means for loading said hopper. 100

2. In an apparatus of the class described, the combination with a frame, of a hopper 105 slidably mounted upon said frame; said hopper including ends and a back and a front piece, a door hinged to said front piece, a scoop-like bottom pivotally mounted upon the ends of said frame, said scoop-like bottom extending at its front end beyond the door, means on the extended end of said bottom for holding the hinged door in a closed position, locking means engaging the extended end of said scoop-like bottom 115 for holding the bottom against pivotal movement, means for locking the hopper within the frame in a fixed position, and means for loading said hopper. 120

3. In an apparatus of the class described, 120 the combination with a frame, of a hopper slidably mounted upon said frame, said hopper including a hinged door and a scoop-like bottom, said scoop-like bottom provided with a front projecting edge, lugs upon said 125 projecting edge and adapted to engage the door for holding it in a closed position, said projecting edge provided at its ends with lugs, manually operated latches on the hopper and engaging the lugs at the ends of said 130

projecting edge for holding the scoop-like bottom in a closed position and thereby holding the door also closed, and means for loading said hopper.

- 5 4. In an apparatus of the class described, the combination with a frame, of a traveling hopper within said frame, said hopper including a front hinged door and a pivotally mounted bottom, said bottom projecting at 10 its front edge beyond the outer face of the door, lugs upon the projecting portion of the bottom and adapted to rest against the front face of the door for holding it in a closed position, lugs formed upon the ends of the 15 bottom outside of the hopper, locking means engaging these last-mentioned lugs for holding the bottom against pivotal movement and thereby holding the door in a closed position upon the hopper, spring-pressed 20 fastening means coöperating with the hopper for retaining it in a fixed position within the frame, and means for loading the hopper.

5. In an apparatus of the class described, 25 the combination with a frame, of a traveling hopper mounted upon said frame, said hop-

per provided with pieces depending from its ends, spring-pressed catches carried by the frame and engaging the depending pieces for holding the hopper in a fixed position 30 within the frame, and means for loading the hopper.

6. In an apparatus of the class described, the combination of a frame including pairs of end standards, brackets secured upon 35 said standards, a traveling hopper within said frame, said hopper provided at its ends with vertical pieces, said pieces extending below the hopper and contiguous to said brackets, catches pivotally mounted upon 40 said bracket and adapted to engage at their outer ends the pieces on the ends of said hopper, coil springs fastened at one end to some of the standards and at their other end to the inner ends of the catches, a lever 45 pivotally mounted upon the frame, rods connected to the lever and to the catches, and means for loading the hopper.

In testimony whereof I hereunto affix my signature.

ARVID R. NELSON.
